UNITED STATES PATENT OFFICE.

ANTONIO C. PESSANO, OF PHILADELPHIA, PENNSYLVANIA, ASSIGNOR TO
THE GEORGE V. CRESSON COMPANY, OF SAME PLACE.

DESIGN FOR A STANDARD FOR JOURNAL-BOXES.

SPECIFICATION forming part of Design No. 32,589, dated April 24, 1900.

Application filed March 19, 1900. Serial No. 9,336. Term of patent 14 years.

To all whom it may concern.

Be it known that I, ANTONIO C. PESSANO, of the city and county of Philadelphia, in the State of Pennsylvania, have invented a new and original Design for Standards for Journal-Boxes, &c., of which the following is a specification.

My new and original design for standards for journal-boxes, &c., is shown in the accompanying drawings, in which—

Figure 1 is a perspective view of a standard embodying the design. Fig. 2 is a front view of the same, and Fig. 3 is a rear view omitting the upper portion.

15 A is a flat circular base bounded by an upturned annular flange *a*.

B is the pedestal, rising from the center of the base A and carrying a widened head C, which is opened and formed of the two sides 20 *c c* and the arched top *b*.

D D are vertical ribs on the exterior of the two sides *c c*, terminating in flattened heads *d*, and *e* is a flattened head or cap on the top *b*.

The lower portion of the pedestal B on one 25 side is of larger diameter than the other side

and forms a thickened portion E, extending over slightly more than half of the circumference and for only part of the vertical height of the pedestal.

F is an elongated opening through the pedestal B, extending through the portion E and bounded on the exterior by a raised rib *f*.

The essential features of the design consist of the flat base A, with the pedestal B rising from the center thereof and carrying the 35 open head C, formed of the sides *c c* and top *b*, with the vertical ribs D D on the outside of the sides *c c*.

What I claim as new, and desire to secure by Letters Patent, is as follows:

40 The design for a standard for journal-boxes substantially as described and shown in the accompanying drawings.

In testimony of which invention I have hereunto set my hand.

ANTONIO C. PESSANO.
